OPEN REFRIGERATED DISPLAY CASE

John R. Caulk, Jr., Ladue, and Russell E. Davis,
St. Louis, Mo., assignors, by mesne assignments,
to C. V. Hill & Company, Inc., Trenton, N. J., a
corporation of New Jersey

Application November 28, 1941, Serial No. 420,797

13 Claims. (Cl. 62—89.6)

Our invention relates to refrigerated display cases, particularly to those of the type in which the merchandise is displayed in an open compartment where it is readily accessible. The invention is particularly applicable to refrigerated display cases for meats and dairy products used in stores of the self service type. The invention has for its principal objects to improve the efficiency of display cases of this general type, to provide for an attractive display compartment and to simplify and improve the construction of the case in general.

The invention consists principally in providing a curtain wall or baffle in front of a cooling mechanism disposed in the top of a case having an open display chamber, said wall or baffle extending below the level of the tops of the walls around said open chamber and fitting tightly against the top and ends of the case. The invention also consists in providing a double baffle construction forming a front flue through which air flows upwardly toward the cooling unit and a rear flue through which chilled air flows downwardly into the display compartment. The invention also consists in the open refrigerated display case and in the parts and combinations and arrangements of parts hereinafter described and claimed.

In the accompanying drawings,

Fig. 1 is a top plan view of an open refrigerated display case embodying my invention,

Fig. 2 is a front elevation with a portion of the glass front wall broken away,

Fig. 3 is an end elevation,

Fig. 4 is a cross sectional view, on an enlarged scale, on the line 4—4 in Fig. 2,

Fig. 5 is a sectional view on the line 5—5 in Fig. 4,

Fig. 6 is a sectional view on the line 6—6 in Fig. 4,

Fig. 7 is a detail perspective view of one of the brackets for holding a baffle member; and

Fig. 8 is a detail partial prospective view of one of the brackets for supporting the members on which the display racks rest.

The case includes a base 1, a relatively high rear wall 2 of insulating material, a relatively low front wall 3 of insulating material, end walls 4 of insulating material having rear portions 5 of the same height as the rear wall 2 and forward portions 6 of the same height as the front wall 3 and a cover 7 extending from the rear wall 2 across the high rear portions 5 of the end walls. Glass plates 8 or other ornamental walls preferably constitute the upper portions of the front wall 3 and similar glass plates 9 constitute the

upper portions of the low forward portions 6 of the end walls, the tops of said glass walls 8 and 9 being considerably lower in height than the rear wall 2. Said rear wall 2, cover 7, front wall 3 and end walls 4 are covered with facings 10 of suitable ornamental material, as porcelain. A suitable light 12, as fluorescent tubing, is mounted along the underside of the forward edge of the cover 7.

10 The merchandise is supported on a foraminous sheet 13 or tray whose forward edge rests on a bracket 14 secured to the front wall 3 and whose rear edge rests on a bracket 15 secured to the front flanges 16 of channel-shaped members 17 whose rear flanges 18 are secured to the rear wall 2. Preferably a plurality of front brackets 14 and rear brackets 15 are provided, mounted at different levels, so that the position of the merchandise supporting tray 13 may be varied. Said merchandise supporting tray is provided with an upstanding strip 19 spaced from its rear edge.

15 The refrigerating mechanism preferably comprises a plurality of tubes 20 with cooling fins 21. Said tubes 20 are supported by hangers 22 secured to the underside of the cover and hanger 23 secured to the rear wall.

The refrigerating mechanism preferably comprises a plurality of tubes 20 with cooling fins 21. Said tubes 20 are supported by hangers 22 secured to the underside of the cover and hanger 23 secured to the rear wall.

20 A curtain wall or baffle 24 composed of insulating material, and preferably inclined rearwardly, extends from a strip 25 projecting downwardly 30 from the cover, to a point below the level of the tops of the glass walls 8 and 9 and the low portions 6 of the end walls 4. Said baffle 24 may be secured in place by means of angle clips 26 secured, as by rivets 27, to said baffle 24 and to plates 28 having flanges 29 secured to the rear wall. Said curtain wall or forward baffle 24 is fitted tightly against said strip 25 and against the end walls 4, to prevent leakage of air that might interfere with the refrigerating cycle. Said baffle 24 is preferably provided with a mirror 30 or other ornamental front facing.

25 Disposed substantially parallel to the front curtain wall or baffle 24 is a rearwardly inclined baffle member 31, comprising a plurality of strips of metal or other suitable material, extending from end to end of the case, with its upper edge at about the level of the lower edges of said radiating fin members 21. Said baffle strips 31 have substantially vertical lips 32 spaced slightly from the forward edges of said radiating fins 21 and substantially vertical lower lips 33. Said baffle strips 31 are secured to said plates 28 by means of angle brackets 34 secured to the plates and to the baffle strips 31. Said rear baffle 31 projects

below the level of the front curtain wall or baffle 24.

A depressed drain trough 35 and a drain pipe 36 are provided to carry away moisture that accumulates during the operation of the device.

The air flow is shown by the arrows in Fig. 4. The cooled air chilled by the refrigerating device 20, being increased in density, flows downwardly between the rear wall 2 and the rear baffle 31 and across the merchandise and into the space 37 below the merchandise. Gradually a pool of cooled air is built up beneath and over the merchandise. The warmer air at the top is drawn into the flue 38 formed by the front baffle 24 and the rear baffle 31 and passes over the refrigerating mechanism.

The rear baffle 31 serves primarily as a drip catcher to divert the drip to the rear of the case, away from the merchandise. The apparatus will function without the rear baffle, the column of chilled air dropping down from the refrigerating device and the warmer air from the top of the display chamber moving upwardly behind the curtain wall 24 and thence into the refrigerating mechanism.

Because of the tendency of the dense, chilled air to stratify, there is little mixing of such chilled air with the hot room air. As the lower edge of the curtain wall is below the level of the top of the glass walls 8 and 9, it will be seen that the upper portion of the pool of chilled air (which is warmer than the air from the refrigerating mechanism, but much cooler than the air in the room) will be drawn into the flue 38 and recirculated. Thus a continuous closed thermosiphon system is created.

The open merchandise chamber can be kept at any desired temperature and the stratifying tendency of dense chilled air minimizes the mixing of air in the refrigerating system with warm room air, thus making the case economical to operate as compared with other open type cases. Other advantages are the provision of an attractive display chamber and the facility for self-service.

Obviously numerous changes may be made without departing from the invention and we do not wish to be limited to the precise construction shown.

What we claim is:

1. A refrigerated display case of the open type, comprising a base, a high rear wall, end walls, a low front wall, a hood projecting from the top of said rear wall and overhanging part of the space between said front and rear walls, a refrigerating device in the top of said case adjacent to said rear wall and above the level of the top of said front wall and a rearwardly inclined curtain wall of insulating material secured to the underside of said hood and tightly fitted thereto and to said end walls, said curtain wall projecting below the level of said front wall.

2. A refrigerated display case of the open type, comprising a base, a high rear wall, end walls, a low front wall, a hood projecting from the top of said rear wall and overhanging part of the space between said front and rear walls, a refrigerating device in the top of said case adjacent to said rear wall and above the level of the top of said front wall, a rearwardly inclined baffle member of insulating material secured to the underside of said hood and tightly fitted thereto and to said end walls, said baffle projecting below the level of said front wall, and a sec-

ond baffle extending from one of said end walls to the other end wall, substantially parallel with said first baffle, the top of said second baffle extending above the level of the bottom of said refrigerating device and above the level of the bottom of said first baffle and the bottom of said second baffle extending below the bottom of said first baffle.

3. A refrigerated display case of the open type, comprising a base, a high rear wall, end walls, a low front wall, a hood projecting from the top of said rear wall and overhanging part of the space between said front and rear walls, a refrigerating device in the top of said case adjacent to said rear wall, a rearwardly inclined baffle member of insulating material secured to the underside of said hood and tightly fitted thereto and to said end walls, said baffle projecting below said refrigerating device and below the level of said front wall, and a second baffle extending from one of said end walls to the other end wall, substantially parallel with said first baffle, the top of said second baffle extending above the level of the bottom of said refrigerating device, the bottom of said second baffle extending below the bottom of said first baffle and said second baffle having substantially vertical lips at top and bottom.

4. A refrigerated display case of the open type, comprising a base, a high rear wall, end walls, a low front wall, a hood projecting from the top of said rear wall and overhanging part of the space between said front and rear walls, a refrigerating device in the top of said case adjacent to said rear wall, a rearwardly inclined baffle member of insulating material secured to the underside of said hood and tightly fitted thereto and to said end walls, said baffle projecting below the level of said front wall, a second baffle extending from one of said end walls to the other end wall, substantially parallel with said first baffle, the top of said second baffle extending above the level of the bottom of said refrigerating device and above the level of the bottom of said first baffle and the bottom of said second baffle extending below the bottom of said first baffle and a foraminous merchandise support above said base and spaced from said rear wall.

5. A refrigerated display case of the open type, comprising a base, a low front wall, a high rear wall, stepped end walls having rear portions of the same height as the rear wall and front portions of the same height as the front wall, a hood projecting from the top of said rear wall and overhanging part of the space between said front and rear walls, a refrigerating device in the top of said case adjacent to said rear wall, a rearwardly inclined baffle member of insulating material secured to the underside of said hood and tightly fitted thereto and to said end walls, said baffle projecting below the level of said front wall and said low portions of said end walls, and a second baffle extending from one of said end walls to the other end wall, substantially parallel with said first baffle, the top of said second baffle extending above the level of the bottom of said refrigerating device and above the level of the bottom of said first baffle and the bottom of said second baffle extending below the bottom of said first baffle.

6. A refrigerated display case of the open type, comprising a base, a high rear wall, end walls, a low front wall, a hood projecting from the top of said rear wall and overhanging part of the space between said front and rear walls, a re-

frigerating device in the top of said case adjacent to said rear wall and above the level of said front wall, a rearwardly inclined baffle member of insulating material secured to the underside of said hood and tightly fitted thereto and to said end walls, said baffle projecting below the level of said front wall, a second baffle extending from one of said end walls to the other end wall, substantially parallel with said first baffle, the top of said second baffle extending above the level of the bottom of said refrigerating device and above the level of the bottom of said first baffle and the bottom of said second baffle extending below the bottom of said first baffle and a foraminous merchandise support above said base and spaced from said rear wall.

7. A refrigerated display case of the open type, comprising a base, a low front wall, a high rear wall, stepped end walls having rear portions of the same height as the rear wall and front portions of the same height as the front wall, a hood projecting from the top of said rear wall and overhanging part of the space between said front and rear walls, a refrigerating device in the top of said case adjacent to said rear wall and above the level of said front wall and said low portions of said end walls, a rearwardly inclined baffle member of insulating material secured to the underside of said hood and tightly fitted thereto and to said end walls, said baffle projecting below the level of said front wall and said low portions of said end walls, and a second baffle extending from one of said end walls to the other end wall, substantially parallel with said first baffle, the top of said second baffle extending above the level of the bottom of said refrigerating device and above the level of the bottom of said first baffle and the bottom of said second baffle extending below the bottom of said first baffle.

8. A refrigerated display case of the open type, comprising a base, a low front wall, a high rear wall, stepped end walls having rear portions of the same height as the rear wall and front portions of the same height as the front wall, a hood projecting from the top of said rear wall and overhanging part of the space between said front and rear walls, a refrigerating device in the top of said case adjacent to said rear wall and above the level of said front wall and said low portions of said end walls, a rearwardly inclined baffle member of insulating material secured to the underside of said hood and tightly fitted thereto and to said end walls, said baffle projecting below the level of said front wall and said low portions of said end walls, and a second baffle extending from one of said end walls to the other end wall, substantially parallel with said first baffle, the top of said second baffle extending above the level of the bottom of said refrigerating device and above the level of the bottom of said first baffle, the body of said second baffle projecting under said refrigerating device and the bottom of said second baffle extending below the bottom of said first baffle.

9. A refrigerated display case of the open type, comprising a base, a high rear wall, end walls, a low front wall, a hood projecting from the top of said rear wall and overhanging part of the space between said front and rear walls, a refrigerating device in the top of said case adjacent to said rear wall and above the level of the top of said front wall, a rearwardly inclined baffle member of insulating material secured to the underside of said hood and tightly

fitted thereto and to said end walls, said baffle projecting below the level of said front wall, a second baffle extending from one of said end walls to the other end wall, substantially parallel with said first baffle, the top of said second baffle extending above the level of the bottom of said refrigerating device and above the level of the bottom of said first baffle and the bottom of said second baffle extending below the bottom of the said first baffle, and a foraminous merchandise tray supported above said base and away from said rear wall, the lower end of said second baffle being to the rear of the rear end of said merchandise tray.

10. A refrigerated display case of the open type, comprising a base, a high rear wall, end walls, a low front wall, a hood projecting from the top of said rear wall and overhanging part of the space between said front and rear walls, a refrigerating device in the top of said case adjacent to said rear wall and above the level of the top of said front wall, a rearwardly inclined baffle member of insulating material secured to the underside of said hood and tightly fitted thereto and to said end walls, said baffle projecting below the level of said front wall, a second baffle extending from one of said end walls to the other end wall, substantially parallel with said first baffle, the top of said second baffle extending above the level of the bottom of said refrigerating device and the bottom of said second baffle extending below the bottom of said first baffle, a foraminous merchandise tray supported above said base and away from said rear wall, the lower end of said second baffle being to the rear of the rear end of said merchandise tray and an upstanding strip on said tray near the rear edge thereof.

11. A refrigerated display case of the open type, comprising a base, a high rear wall, end walls, a low front wall, a hood projecting from the top of said rear wall and overhanging part of the space between said front and rear walls, a refrigerating device in the top of said case adjacent to said rear wall and above the level of the top of said front wall, a depending baffle member of insulating material secured to the underside of said hood and tightly fitted thereto and to said end walls, said baffle projecting below the level of said front wall, and a second baffle extending from one of said end walls to the other end wall, substantially parallel with said first baffle, the top of said second baffle being below the top of the refrigerating device and extending above the level of the bottom of said refrigerating device and above the level of the bottom of said first baffle and the bottom of said second baffle extending below the bottom of said first baffle.

12. A refrigerated display case of the open type, comprising a base, a rear wall and a pair of end walls extending upwardly from said base, a front wall extending upwardly from said base to a lesser height than said rear wall, a hood projecting from the top of said rear wall and secured to said end walls and overhanging a part of the space between said front and rear walls, a refrigerating device in the top of said case adjacent to said rear wall and above the level of the top of said front wall, said hood including an element extending substantially parallel to said rear wall from one of said end walls to the other, and a curtain wall inclining downwardly from said element toward said rear wall to a

level below said refrigerating device and not above the top edge of said front wall.

13. A refrigerated display case of the open type, comprising a base, a high rear wall, end walls, a low front wall, a hood projecting from the top of said rear wall and overhanging part of the space between said front and rear walls, a refrigerating device in the top of said case adjacent to said rear wall and above the level of the top of said front wall, a rearwardly inclined baffle member of insulating material secured to the underside of said hood and tightly fitted thereto and to said end walls, said baffle projecting below the level of said front wall, a sec-

5   10   ond baffle extending from one of said end walls to the other, substantially parallel with said first baffle, the top of said second baffle extending above the level of the bottom of said refrigerating device and the bottom of said second baffle extending below the bottom of said first baffle, and a foraminous merchandise tray supported above said base and away from said rear wall, the lower end of said second baffle being to the rear of the rear end of said merchandise tray.

JOHN R. CAULK, JR.
